United States Patent Office.

WILLIAM W. VANDERBILT, OF NEW YORK, N. Y.

Letters Patent No. 91,796, dated June 22, 1869.

VENTILATOR FOR SHIPS.

The Schedule referred to in these Letters Patent and making part of the same.

To all whom it may concern:

Be it known that I, WILLIAM W. VANDERBILT, of New York, in the county of New York, and State of New York, have invented a new and useful Method of Ventilating Vessels, particularly adapted for cabins and state-rooms; and I hereby declare the following to be a full, clear, and exact description of the same.

The object of my invention is to place within the power and under the control of passengers, a simple and efficient arrangement to ventilate their apartments under all conditions of weather; that is to say, to provide for a steady influx of pure atmospheric air, and for the discharge of air which is vitiated by respiration, combustion, or other causes.

The common windsail and similar devices for accomplishing this purpose, simply displace the noxious vapors, by mixing pure air with them; and in consequence thereof, only ventilate that part of the vessel in which they are situated.

Side-light openings simply ventilate the apartments in which they open, and cannot be used in stormy weather.

My invention consists essentially in forming a ventilator of a space between the hurricane-deck and the ceilings of the state-rooms and cabins.

I place, in the ceiling of each state-room, two registers, with adjustable vanes, under the control of the occupant of the room, the vanes so arranged as to point in opposite directions, so that the air, in its passage athwartships, will be deflected into the room by the vanes of one register, and its passage over the vanes of the other register will so rarefy the air in the room as to cause an upward current, serving to exhaust the room of foul air, thus keeping up a circulation as long as desirable.

In the accompanying drawings, like letters refer to like parts.

Figure 1, plate 1, is an athwartship-section of the vessel through the state-rooms;

Figure 2 is a top view, showing the registers and partitions;

Figure 3 is a side view; and

Figure 4 is a side view of the registers and the rod F, which operates the register to ventilate the lower state-room B.

In the ceiling of the upper state-room A, are two registers, C, opening into the athwartship-passages H, between the beams of the deck.

The registers, figs. 2 and 4, consist of light frames of brass or other suitable material, with movable vanes of the same material.

The vanes are connected with each other, and with handles, and in the lower state-room, with the rod F.

These vanes can be inclined, at will, in opposite directions, or entirely closed.

The interior of the lower state-room B is connected with the space H, by means of the conduits or tubes, E, which have each a register in the upper end, adjusted by the rod F, so that the occupant of the lower state-room has a means of ventilation entirely under his control. I claim as new and useful, and desire to secure by Letters Patent—

The partitioned passages H open at their ends, and situated between the ceilings of the upper state-rooms and the hurricane-deck, in combination with the registers C and conduits E, all constructed, arranged, and operated in the manner and for the purpose set forth.

WILLIAM W. VANDERBILT.
